UNITED STATES PATENT OFFICE.

PEDER ANDERSEN FISKER, OF COPENHAGEN, DENMARK.

REGULATING DEVICE FOR CYCLES.

1,317,081.

Specification of Letters Patent. Patented Sept. 23, 1919.

Application filed May 4, 1918. Serial No. 232,672.

To all whom it may concern:

Be it known that I, PEDER ANDERSEN FISKER, a subject of the Kingdom of Denmark, residing at No. 30 Peder Bangsvej, in the 5 city of Copenhagen and Kingdom of Denmark, have invented certain new and useful Improvements in Regulating Devices for Cycles; and he does hereby declare the following to be a full, clear, and exact description of the invention, such as will enable others skilled in the art to which it appertains to make and use the same.

This invention relates to improvements in regulating devices for the motors, &c. of 15 cycles disposed in connection with the handles of the cycles, and is essentially characterized by the fact that two or more regulating wires, which are in a known manner led through the interior of the steering 20 handle, are controlled independently of each other by means of devices connected with said handle, one of said wires—or several wires disposed in the same manner—being tightened and slackened by turning the 25 handle, which movement does not influence the other wires, while these wires are tightened and slackened by means of levers which have no effect upon the first mentioned wires.

30 A constructional form of a device constructed in accordance with the invention is represented in the drawing, the device shown being provided for the sake of simplicity with two wires only. Figure 1 is a 35 longitudinal section through the device, Fig. 2 an end elevation of the same, while Fig. 3 shows schematically a detail of a somewhat modified form.

40 α represents the tube forming the steering member of the cycle and upon which a short tube b carrying the handle c may be turned. The tube b is held and controlled on the end of the steering device α by means of a bushing d which is provided with an 45 outwardly extending flange e , which extends across an inwardly extending flange f on the tube b . The bushing is preferably provided with two branches g , h carrying a pin or the like i on which are pivoted two 50 levers j , k connected at their inner ends with inwardly directed wire, cables or other flexible elements, l , m respectively.

According to the invention the wires l , m are moved independently of each other, the 55 wire l being tightened and slackened by a pressure upon the lever n which is integral

with the lever j , the movement of which has no influence upon the wire m , while the latter is tightened and slackened by turning the handle c and the tube b connected therewith. To this end the lever k is provided with a shoulder o riding upon an inclined surface or extension p which may be formed either on the tube b or on the bushing d , thus slackening the wire when the shoulder slides down the inclined surface p and tightening it when it slides up the same.

If it is desired to regulate more than two wires from one and the same handle, more 70 than one lever n is provided, or two or more levers k are arranged to work together with corresponding inclined surfaces p . Obviously two or more levers of both kinds may be provided.

In the case of two levers being employed the inclined surfaces of the bushing d may be arranged as shown in Fig. 3 so that the turning to one or the other side slackens or tightens only one of the wires, the shoulder o on one lever co-acting with an inclined surface p as described, while the shoulder o on the other lever co-acts with an oppositely directed inclined surface p . Between the surfaces p , P there is a a non-inclined 85 surface somewhat longer than the distance between the shoulders o , O .

Claims.

1. The combination of a tubular element comprising concentric inner and outer members, one of which is rotatable with relation to the other; a fixed cam on one of said members; a lever pivotally connected with the other member for operative engagement with said cam to be rocked by the latter 90 when rotatable member is rotated; and a cable passing through said members and connected to said lever.

2. The combination of outer and inner tubular members, the outer member being 100 provided with an inclined surface and being rotatable upon the inner member; a tubular handle fixed to the outer member; a bushing secured in the inner member; a lever pivotally connected to said bushing 105 and adapted to engage said inclined surface to be rocked thereby consequent upon the rotation of the outer member; and a cable passing through said members and said bushing and connected to said lever to be 110 operated when the lever is rocked.

3. The combination of outer and inner

tubular members, one rotatable upon the other; a handle fixed to the outer member; a bushing secured in the inner member; a cable passing through said members and 5 said bushing; a lever having said cable connected to it; a cam operatively engaging said lever to rock the same; said cam and lever constituting companion parts one of which is caused to rotate when the rotatable member is rotated.

4. The combination of outer and inner tubular members, one rotatable upon the other, the outer member being provided with a pair of oppositely-inclined surfaces

and with a straight connecting portion 15 therebetween; a pair of levers pivotally connected with the inner member for engagement with said inclined and straight surfaces to be alternatively and independently rocked by the inclined surfaces consequent upon the rotation of the rotatable member in one direction or the other; and a plurality of cables passing through said members, each lever having at least one cable individually connected to it. 20 25

In testimony whereof, I affix my signature.

PEDER ANDERSEN FISKER.
